UNITED STATES PATENT OFFICE.

LUIGI GUIDO SCARPA, OF TURIN, ITALY.

SURGICAL APPLIANCE.

No. 894,066.

Specification of Letters Patent.

Patented July 21, 1908.

Application filed June 25, 1907. Serial No. 380,768.

To all whom it may concern:

Be it known that I, LUIGI GUIDO SCARPA, a subject of the King of Italy, residing in Turin, Via della Zecca N. 37, physician, have 5 invented certain new and useful Improvements in Surgical Appliances, of which the following is a full, clear, and exact specification.

My invention is an improvement in surgical 10 apparatus for the treatment of pulmonary troubles, and consists in certain novel constructions and combination of parts hereinafter described and claimed.

The invention is illustrated in the accompanying drawings, in which

Figure 1 is a complete view of the improvement. Fig. 2 is a view of the portion intended for compressing the thorax, the device being in its open position. Fig. 3 is a section on 20 the line *a*—*b* of Fig. 2. Fig. 4 is a support *S* or device for fixing the half 1 which is provided with a pneumatic cushion in substitution for the half 2 which is illustrated by the drawings. Fig. 5 illustrates the improvement in 25 its open position so that only that portion *p* *p* *p* is seen, which is intended for the compression of the base of the thorax.

The first of these devices, is substantially composed of two parts:

(a) A sort of half waistcoat 1 corresponding 30 to the one or the other half of the thorax, constructed of an inextensible layer of linen, on the inside of which is a pneumatic cushion *p* *p* *p* the shape of which corresponds to that of the waist-coat, leaving free 35 only the portion which covers the shoulder, that is to say from the second rib upwards; this pneumatic cushion is constructed of perfectly air-tight material and when filled with 40 air has a thickness of about a centimeter. A small metallic pipe *t* is situated in a certain point of the lower edge of the apparatus in the continuation of the arm-pit region, and is connected with a short indiarubber tube 45 provided with a valve *r* which allows its inflation with an ordinary foot-ball inflator. This lower edge of this half-waistcoat continues with a horizontal band formed of a strong linen strip *f*, which operates as a girdle 50 surrounding the whole circumference of the body in the epigastric region, from the arch of the ribs to the navel. This horizontal

band has the double result of limiting the movements of the diaphragm downwards by compressing the high portion of the abdominal walls, and of fixing the device in its lower position by means of two continuations provided with buckles *x* *x* which may be tied between the arch of the ribs and the upper edge of the haunchbone of the opposite side. 60

(b) A half breast casing 2 formed by four thin vertical plates of nickeled steel or aluminium; two plates on the anterior and two on the posterior side, and are united by means of two other transversal plates which 65 are adapted to the two opposite portions of the thorax; the diameters of this casing are about 6 centimeters larger than the corresponding diameters of the thorax which is under it, so that this may take the greatest 70 possible expansion without being compressed when coming in contact with it. The purpose of this half casing is to provide a point of support in its upper half, that is to say at the level of the shoulder, to the other half of 75 the device, which is provided with the pneumatic cushion, this point of support being formed by a sort of metallic epaulet *S* of such a form to suit perfectly the shoulder, and movable by means of a simple device in 80 its vertical and transverse directions to suit different forms and position of the shoulder on different persons. These halves 1 and 2 are united on the middle line of the anterior and posterior side by strings *l* *l* and small 85 hooks which rigidly connect the two parts, so that the half that is swelled in consequence of the filling of its air cushion, cannot be moved and must remain adherent to the corresponding half of the thorax opposing the dilation 90 movements of the ribs, which are so compelled to remain in their position of extreme expiration, while the epigastric band *f* completes the result, by limiting the movements of the diaphragm which by way of compensation should tend to increase very much. Instead of the whole thoracic casing 2 and in 95 order to have a more simple and rapid means of fixing the half which is provided with the pneumatic cushion in those cases when the patient is not compelled to remain with his usual dress, a support *S* may be employed (Fig. 4) that is to say a steel-rod of a *U* form with its opening downwards, which is of a

convenient form to suit the side of the thorax on which the half casing must be placed. The curved part of the **U** projects above the corresponding shoulder, and its two vertical 5 prolongations A and B are contained in a vertical plane tangent to the part of the thorax that corresponds to the arm-pit region; A and B extend downwards to two guides p^2 and p^1 on which they are fixed by means of a pair of 10 screw plugs, which are provided on the exterior convex face of a plate L having a length of 20 centimeters, a height of about 4 centimeters and a thickness of 3-4 millimeters; this plate is slightly concave in the antero-posterior direction of its vertical plane 15 and with its concave surface surrounds and rests on the corresponding side between the arch of the ribs and the edge of the haunch-bone.

20 By means of the guides of the plate L, the two prolongations A and B of the support (said prolongations being provided with small hooks $u\ u\ u$ to which the connection with the half provided with the pneumatic cushion is possible by means of the strings $l\ l\ l$,) may be slid upwards or downwards in 25 order to lengthen or shorten the support itself to suit the thorax of different persons.

At the level of the shoulder the support is 30 of course provided with the metallic epau-let S which gives the other, that is to say the upper point of support on the shoulder. The distance between the two vertical pro-35 longations A and B, varies from 20 to 30 centimeters according to the development of the thorax to which it is to be adapted. This support may be fixed around the body at the level of the navel by means of straps provided with buckles. The other appa-40 ratus shown in Fig. 3, is analogous to the apparatus described above in its functions and its results, that is to say in the immovability that may be obtained of one of the halves of the thorax to the advantage of the 45 functional activity of the other half, which receives an almost incredible increase in its functional activity. The reason of this con-sists in the fact well demonstrated and easy to be ascertained that it is possible to sepa-50 rate in the same lungs the functional activity of its upper and lower part—so that produc-ing the immovability of the lower or basilar parts of the thorax, a very great augmentation of the functional activity of the upper 55 parts, that is of the superior lobes of the lungs may be obtained. This apparatus which is shown in Fig. 3 consists of a rectan-gular band of inextensible lining M N, having a length of 60 to 80 centimeters and a height 60 of 13 to 18 centimeters, in which the shaded rectangle $p\ p\ p\ p$ shows the cushion to be filled with air by means of a metallic tube t situated at the base of the left arm-pit

region, continuing in an india-rubber tube the end of which is provided with a valve r . 65 By means of straps provided with buckles x , x , the said band with which the inferior part of thorax is surrounded from the level of the nipple downwards, may be buckled along the middle line of the body's posterior 70 part, and after being filled with air, it gives by necessity of compensation a very great increase of the activity of the upper half of the thorax which may freely make its move-75 ments of inhalation and expiration. This apparatus continues downwards with the said epigastric band constructed of resistant lining, which compressing the body between the arch of the ribs and the navel has the result of pressing the epigastric region, limit-80 ing the movements of the diaphragm.

The mode of working of both devices is very easily understood if one considers that by means of the inflation of the pneumatic cushion which is maintained in contact with 85 one of the two thoracic halves or of the basilar part of the whole thorax, in conse-90 quence of the inextensibility of the lining which forms the exterior surface, the space only at expense of a depression on the whole part of the thorax which must necessarily take its position of expiration.

What I claim is:

1. Means for immobilizing a portion of the 95 thorax whereby to increase the functional activity of the remainder thereof, comprising an inextensible lining, an inflatable cushion on the inner face thereof, a support for the lining on the opposite side of the body and 100 connected therewith, and a band connected with the bottom of the lining for encircling the body of the wearer.

2. Means for immobilizing a portion of the 105 thorax, said means comprising an extensible lining, an inflatable cushion on the inner face thereof, a band connected with the bottom of the lining for encircling the body of the wearer, an open frame for inclosing the oppo-110 site side of the body, and a connection be-tween said frame and the lining.

3. Means for immobilizing a portion of the 115 thorax, said means comprising an inexten-sible lining, an inflatable cushion on the inner face thereof, a band connected with the bot-tom of the lining for encircling the body of the wearer, an open frame on the opposite side of the body and connected with the lining for supporting the same, and a shoul-120 der-piece for engaging the curve of the shoul-der and connected with the frame.

4. Means for immobilizing a portion of the 125 thorax, comprising an inextensible lining, an inflatable cushion on the inner face thereof, a band connected with the bottom of the lining for encircling the body of the wearer,

an open frame on the opposite side of the body, a connection between the frame and the lining for supporting said lining, a shoulder-piece for engaging the curve of the shoulder on the opposite side from the lining, and a connection between the shoulder-piece and the frame.

In witness whereof, I have hereunto signed my name in the presence of two subscribing witnesses.

LUIGI GUIDO SCARPA.
